STAGE CURTAIN RIGGING

Charles E. Tompkins, Syracuse, N. Y., assignor to
 J. R. Clancy, Inc., Syracuse, N. Y., a corporation
 of New York

Application December 28, 1937, Serial No. 182,130

1 Claim. (Cl. 254—141)

My invention relates to rigging for raising and lowering a stage curtain and more particularly to means for taking up the slack or stretch in the purchase line of such rigging.

An object of my invention is to provide a stage curtain rigging wherein a slidable block is provided over which the purchase line is passed for taking up the slack caused by stretching of the rope, and the provision of means for maintaining said purchase line taut in use.

More specifically, my invention contemplates the provision of a stage curtain rigging wherein the purchase line for raising and lowering the curtain is passed over a sheave in a block slidable on guides, the block being provided with means for preventing movement of the block in one direction while at the same time enabling its movement in the opposite direction under the action of gravity to thereby tauten the purchase line.

Other objects and advantages of my invention will be more apparent from the following description when taken in connection with the accompanying drawing, in which:

Figure 1 is a perspective view showing the floor block of a stage curtain rigging in which my invention is incorporated.

Figure 2 is a view of a portion of Figure 1 showing the locking device for preventing movement of the block in one direction.

Figure 3 is a view similar to Figure 2 except that it is partly in section.

Figure 4 is a perspective view of the locking device.

The floor block in which my invention is incorporated may be used in a conventional stage curtain rigging or may be used as a substitute for the floor block shown in my application filed December 17, 1937, Serial No. 180,471, now Patent No. 2,142,063, issued December 27, 1938.

In general, a stage curtain rigging system comprises a plurality of curtain supporting ropes which are operatively connected to a counter-weight slidably in suitable guides. The counter-weight is adapted to counter-balance the weight of the curtain. The counter-weight is also operatively connected to a purchase line through which the curtain is raised and lowered. The purchase line is passed over a plurality of sheaves so that upon pulling upon the purchase line in one direction the counter-weight is raised and the curtain lowered, and upon pulling on the purchase line in the opposite direction the counter-weight is lowered and the curtain raised. The purchase line of such systems, in use,

stretches so that in many installations a floor block is provided which is slidable or movable on guides so that the slack in the purchase line is automatically taken up as it stretches. In the past, one of the disadvantages of such movable floor blocks for taking up the slack has been that when the purchase line is pulled upward the floor block has a tendency to move or slide upward with it. Then when the purchase line is released, the floor block moves or slides downward, causing a considerable noise back-stage which is extremely objectionable.

In my invention, I have provided a slidable floor block with means for preventing the upward movement of the block when the purchase line is raised while still enabling the floor block to move downward on its guides as the purchase line stretches under the action of gravity to thereby take up the slack.

In Figure 1, I have shown a slidable floor block, indicated generally by the numeral 10, which is mounted on a platform or base plate 11 adapted to be bolted or otherwise secured to the rigging floor. The base plate 11 has secured therein, in any suitable manner, a plurality of guides 12. A cross bar 15 is adapted to receive the tops of the guides and maintain the structure rigid. The guides are slidably received in apertures provided in bosses or lugs 13 formed in this instance integral with a pair of plates 16, four on each plate. The plates 16 constitute a sheave block and are secured together in any suitable manner. If desired, cross rods 17 may be used. Rotatably mounted on a shaft 18, carried by the plates 16, is a sheave 19 adapted to receive a pull rope or purchase line 21.

It will be appreciated that in the ordinary stage curtain rigging in which a slidable block is provided, an upward pull on the purchase line to raise the curtain tends to raise with it the slidable block upward on its guides. As soon as the purchase line is released, the block slides down on its guides causing a considerable noise. I have provided simple means of preventing this from occurring.

As shown more clearly in Figures 2, 3 and 4, a locking device, indicated generally by the numeral 20, is provided comprising a plate 22 having riveted thereto, as indicated at 23, a U-shaped member 24 having legs 26. The plate 22 is provided with an aperture 27 which is adapted to encircle one of the guides 12. The locking device 20 is placed in operative position by loosely mounting it on top of one of the plates 16, as indicated in Figure 2, in such position that the legs 26

26 loosely straddle the plate. The aperture 27 is somewhat larger in diameter than the guide so that the locking device tends to hang downward in angular relationship to the guide 12, as indicated in Figures 2 and 3. While a locking device 5 may be provided at each end of each of the plates, I have found that one locking device is sufficient, although I have shown two in the drawing, one mounted on each plate.

10 A further advantage of my structure, as shown in dotted lines in Figure 2, is that the lock 20 may be raised upward clear of the plate 16 and rotated from the solid line position of Figure 2 to the dotted line position of that figure. This 15 enables free movement of the block upward whereby adjustment of the pull rope may be made. Further, if a theatre is shut down for any appreciable period, the locking device may be moved to its inoperative position so that expansion and contraction of the pull rope due to temperature or humidity changes is freely permitted.

15 It will now be appreciated that when the purchase line 21 is pulled upward, the margins of the aperture 27 will dig into the guides, as indicated 20 at 28 and 29 in Figure 3, and prevent upward movement of the block. At the same time, it will be appreciated that downward sliding movement of the block on its guides under the action of gravity as the rope stretches in use is freely permitted. 25 The upward and downward movement of the block during the normal operation of the stage curtain rigging and the consequent noise is thereby eliminated.

While I have shown an exceedingly simple way of accomplishing my desired result, it will be appreciated that various changes and modifications may be made without departing from the spirit of my invention as set forth in the appended 5 claim.

I claim:

In a rigging for raising and lowering a stage curtain, a pull rope by which said curtain is raised and lowered, and means for taking up the slack in said pull rope as said rope stretches in use comprising a slideable block having a sheave over which said pull rope is passed, guides for said block, a lock member slidably and rotatably mounted on one of said guides adjacent said block by means of an aperture through which said guide passes, said aperture being larger than said guide, said block having two surfaces adapted to cooperate with said lock member in two positions of rotation thereof, one a locking position 15 and the other an unlocked position, said lock member when in its locking position being held by the cooperating block surface with said aperture inclined to said guide whereby said lock member and guide together constitute a jam 20 clutch restraining said block against movement in one direction, and said locking member when in its unlocked position being held by the cooperating block surface with said aperture substantially coaxial with said guide whereby said block is 25 free to move in either direction along said guides.

CHARLES E. TOMPKINS.
